(57) **CLAIM**

What is claimed is the ornamental design for a cellular telephone label media sheet, as shown and described.

DESCRIPTION

FIG. 1 is a top plan view of the cellular telephone label media sheet, showing my new design: and,

FIG. 2 is a top plan view of a second embodiment the cellular telephone label media sheet.

In the drawings, the broken lines are for illustrative purposes only and form no part of the claimed design. The bottom view of each embodiment forms no part of the claimed design.

1 Claim, 2 Drawing Sheets

FIG. 1

FIG. 2
